UNITED STATES PATENT OFFICE

2,080,382

HAT AND THE MANUFACTURE THEREOF

Earl Siegel, Chicago, Ill., assignor to Grand Trimmed Hat Mfg. Co., Chicago, Ill., a corporation of Illinois

Application November 16, 1936, Serial No. 111,044

1 Claim. (Cl. 2—192)

This invention relates to hats and the manufacture thereof, and more particularly, to hats of the type usually worn by women.

Women's type hats are fabricated from various materials such as felt, straw, fabric, paper and various compositions, and are constructed in devious ways. One extensively used commercial construction forms a hat from what is known as a body, which is composed of a single 5 piece of material of substantially circular cross section throughout its height. For economy in shipment in such bodies to manufacturers, they are desirably collapsed or rolled for convenience in packing.

15 As a general rule, most women purchase a number of hats during the year, and the matter of the cost of production has long been a matter of concern to this industry. Hats as produced at the present time, necessitate a substantial investment in equipment, and if the hats 20 are produced mainly by hand, the cost of same frequently results in a restricted market outlet.

The present invention therefore, has for one of its main objects, the provision of a novel hat construction, and an improved novel method of 25 producing same, and which may, at the same time, be economically manufactured.

Another object is to produce a hat from a single piece of material having a cushion brim formed by a double thickness of said material.

30 A further object is to provide an improved hat construction which permits using smaller bodies of single piece of material than customarily used, thus resulting in a saving of material.

35 Still another object of this invention resides in a novel hat construction and method of producing the same, which permits obtaining novel style effects which were not heretofore available.

40 And a still further object of this invention is to produce an improved hat construction and method of manufacturing the same, which permits a substantial saving in labor and equipment, and which, at the same time, eliminates 45 a substantial amount of hand work generally necessary in hat construction.

With the foregoing and other objects in view, which will appear as the description proceeds, 50 the invention consists in certain novel features of construction, arrangement and combination of parts hereinafter more fully described and illustrated in the accompanying drawing, and particularly pointed out in the appended claim, 55 it being understood that various changes in the

form, proportion, size and minor details of the construction may be made without departing from the spirit or sacrificing any of the advantages of the invention.

Referring to the drawing, in which the same 5 characters of reference are employed to designate corresponding or similar parts throughout the several figures of the drawing:

Fig. 1 is a perspective view of one type of hat body which may be used in carrying out the 10 present invention;

Fig. 2 is a view similar to Fig. 1, showing a head opening cut into the wall of the crown;

Fig. 3 is a view similar to Fig. 2, showing a sweat band in process of being secured around 15 the head opening;

Fig. 4 shows the hat body in collapsed form placed over a form;

Fig. 5 shows the body with the brim formed with certain novel style effects.

Referring now to the drawing more specifically by characters of reference, the hat body is generally indicated by reference character 10, which is of a common type now used commercially and known in the trade as the (hood) style. The said body, it will be understood, has been selected for purpose of illustration, and may be formed of various materials, such as 20 felt, fabric, straw, paper or various compositions. The said body may also assume, instead 30 of the shape illustrated, other shapes, such for example, as the (capeline) style, which is also commonly used, and which differs from the (hood) style, in that it is provided with a relatively distinctly formed brim. This type of body 35 also lends itself equally well for use, in accordance with the present invention.

The wall of the crown portion, indicated at 11 of the hat body, is formed with a head opening 12, which preferably, though not essentially, is 40 of oval conformation and is located so that the upper marginal edge thereof is in close proximity to the top of the crown. A suitable sweat band 14 of suitable material is secured to said wall 45 of the crown surrounding the said head opening 12.

After the completion of the formation of the head opening in the side of the crown, the next step in my improved process is to collapse the hat body to substantially the position shown in Fig. 4, and to place the same over a suitable form 50 15, having a curved dome portion 16, which extends through the head opening 12, as seen in the drawing for assisting in rounding out the head form in the opposite wall of the crown. In 55

this manner, the head portion is formed, as indicated at 17, which portion, it will be noted, is provided with substantially no brim at the rear thereof, and with a relatively large double walled brim or visor at the forward end thereof. In other words, when the body 10 is collapsed and mounted on the form in the manner illustrated in Fig. 4, the wall of the entire body below said head opening, forms a continuous brim 18, composed of super-imposed wall portions, 19 and 20, extending in a forwardly direction. In actual practice, the said brim will assume a substantially fan-like shape and will be of probably less than 120° arcuate extent.

15 The two layers of material, 19 and 20, constituting the brim, produce what is known in the trade as a cushion brim, and the edges thereof may, if desired, be secured or permitted to remain free, the latter being known in the trade as an 20 open cushion brim, and the former as a closed cushion brim. While the hat body is on the form 15, it may be shaped to a desired style and held in place by suitable pins, and after the complete hat has been shaped, it may be pressed in 25 said shape, the pins removed, and the hat construction completed.

In Fig. 5 there is illustrated some of the style effects that may be given to the portions 19 and 20 for producing the desired ornamental effects 30 from the material of the body itself. Thus, as shown in said figure, the lower portion 19 is provided with a number of plaits 21, whereas the upper portion 20 may be provided with a relatively 35 large plait, 22, formed adjacent its middle. The brim portion, 18, may also be provided with the plaits 23, as shown in Fig. 5 in one edge thereof, adjacent the crown portion 17. For a finished appearance, the outer wall of the crown surrounding the head opening 12, may have a band 40 or ribbon, 24, situated thereto, as shown in Fig. 5.

It will be understood that the style effect produced by the plaiting illustrated in Fig. 5 is merely illustrative of what may be done towards producing desired ornamentation or desired style effects, as obviously the portions 19 and 20 may be worked upon to produce many different varieties of plaiting, thereby varying the effect of the 45 finished hat.

It should be readily understood that this novel

method of constructing the hat readily lends itself to the production of a large variety of novel style effects, such as forward trend; forward and upward trend; roll-off the face; beret; visor brim effect; flange cushion. In the formation of these 5 various styles the brim may be either of the open or closed cushion type, and in either case, it may be novelly shaped or formed and draped to produce style effects that have never heretofore been attained. If desired, various other forms of ornamentation may be added to the finished hat, such as ribbons, flowers, feathers, and various decorative elements. However, such additional decoration, in most instances, will be unnecessary, as the material from the body itself may be readily and effectively utilized for producing the necessary decorative or ornamental effect for the finished product.

Hats constructed in accordance with this invention, it will be noted, require a reduced quantity of material, less labor, and results in a novel and improved hat construction that is capable of economical manufacture, while at the same time resulting in a finely finished product.

It is believed that my invention, its mode of 25 construction and assembly, and method of construction, and many of its advantages should be readily understood from the foregoing, without further description, and should also be manifest that while a preferred embodiment of the invention has been shown and described for illustrative purposes, the structural details are, nevertheless, capable of wide variation within the purview of my invention as defined in the appended 30 claim.

What I claim and desire to secure by Letters 35 Patent of the United States is:

An improved method of manufacturing hats formed from a hat body having side walls, a closed end and an opposite open end, which comprises forming a head opening in the side wall adjacent the closed end, folding the body together and placing on a form which extends into said opening so as to form a crown from the side wall disposed opposite said opening, said body being so folded that the corresponding wall portions below said opening will be in super-imposed relation to constitute a brim, and imparting desired 40 configuration or ornamentation to said brim portion of the body.

EARL SIEGEL.
